United States Patent Office

Des. 219,283
Patented Nov. 24, 1970

219,283

TOY SPACE SHIP

Jack Rosenthal, South London, England, assignor to
Rovex Industries, Ltd., London, England, a corpora-
tion of Great Britain

Filed Jan. 5, 1970, Ser. No. 21,063

Term of patent 3½ years

Int. Cl. D21—02

U.S. Cl. D34—15

FIG. 2.

FIG. 1.

FIG. 3.

FIG. 1 is a side elevational view showing the design
of a toy space ship according to the invention;

FIG. 2 is a top plan view; and

FIG. 3 is a bottom plan view; and

FIG. 4 is a front elevational view; and

FIG. 5 is a rear elevational view.

I claim:

The ornamental design for a toy space ship, substan-
tially as shown.
